VIEWING AND ILLUMINATING DEVICE FOR
DIVERS' HELMETS

Andrew Barna, South Chicago, Ill.

Application December 15, 1944, Serial No. 568,380

3 Claims. (Cl. 88—1)

1

This invention relates to improvements in divers' helmets and its purpose is to provide an improved underwater helmet adapted to be worn by a diver when carrying on welding operations under water with the use of a welding torch.

Welding operations have heretofore been carried on under water but in a rather unsatisfactory manner because of the deficiencies of the diver's equipment. The usual diver's helmet employed for the purpose is equipped with colored glass to enable the diver to look at the torch flame while welding but this colored lens has interfered with his vision when looking around in the dark water to locate the work after being lowered from the surface. A further disadvantage has been that the diver has been compelled to feel his way while welding because the steam produced by the torch in the water has caused such a flow of bubbles as to obscure his vision of the site of the weld. While it has been possible for a diver to feel his way with some success when welding a lap joint because of the guiding shoulder formed by the overlap, it has been impossible for a diver to weld satisfactorily a butt joint, such as that presented by a crack in the hull of a sunken vessel, for example, because of his inability to follow the crack with the torch.

The principal object of the present invention is to overcome the above-mentioned difficulties and others, by providing an attachment for a diver's helmet whereby there is created a strong current away from the helmet and beyond the place of welding, thereby insuring against the presence of bubbles, steam and sparks which tend to obscure the vision. A further object is to provide a helmet having a clear glass lens through which the diver may view his surroundings under water while locating the work, in combination with a helmet extension or attachment which may then be swung into position to permit the diver to look through a colored lens while working. Another object is to provide a device adapted to be attached to a diver's helmet for use in underwater welding and including means for illuminating the site of the weld. A further object is to provide an attachment, capable of being applied to any diver's helmet, to cause jets of water to clear the vision of the diver at the site of the weld. Still another object is to provide a diver's helmet having a tubular extension equipped with a ground glass magnifying lens which may be adjusted longitudinally of its focal axis to give the diver proper vision of the work during welding.

2

More particularly, the invention comprises the combination with a diver's helmet equipped with a clear glass lens of a hinged tubular extension which may be swung to a position over said lens and which has mounted therein a colored glass plate through which the welding operation may be viewed, the mouth of the extension having mounted around it a nozzle arranged to project jets of water under pressure in paths defining a cone, thereby causing the sparks, steam and bubbles to be carried by the jets out of the cone-shaped area enclosed by the jets, thereby providing a clear working area in which welding operations may be carried on, this welding region being preferably illuminated by lamps mounted on the tubular extension. A magnifying lens is preferably adjustably mounted in the tubular attachment to permit the diver to obtain a better view of the work.

20 These and other objects of the invention will appear more clearly from the following specification taken with the accompanying drawings in which one embodiment of the invention is illustrated.

25 In the drawings,

Figure 1 shows a side elevation of a diver's helmet embodying the improvements of the present invention;

Fig. 2 shows a sectional view taken on the line 2—2 of Figs. 1 and 5;

Fig. 3 shows an enlarged sectional view taken on the line 3—3 of Fig. 1;

Fig. 4 shows an enlarged front elevation of the diver's helmet shown in Fig. 1; and

35 Fig. 5 shows a longitudinal vertical section taken on the line 5—5 of Fig. 4.

As illustrated in the drawings, the improved attachment of the invention is applied to a diver's outfit comprising a body portion 10 having a top flange 10^a upon which there is seated a rubber gasket 11, this gasket being interposed between the flange 10^a and the flange 12^a of the helmet 12. The flange 12^a extends outwardly from the neck portion 12^b of the helmet and is secured to the flange 10^a of the body portion by a series of studs 13. The helmet 12 is provided at its top with an inlet 12^c adapted to be connected through a flexible hose 15 with a source of compressed air located at the surface of the water so that air may be supplied to the diver when he is submerged. The helmet 12 is provided on its front side with an outlet 12^d surrounded by a flange 12^e and a clear glass lens 16 is mounted over this outlet opening, being seated in place against an annular shoulder

formed on the inside on the flange 12^a and being engaged on its outer side by a rubber gasket 17. A metal ring 18 engages the outer side of the gasket 17 and these parts are secured to the flange 12^a of the helmet by means of a series of screws 19. These parts correspond to those commonly used in divers' helmets except that the lens 16 is formed as clear glass to facilitate the diver's view of his surroundings after he has been lowered from the surface and during the time that he is walking about on the bottom of the sea, lake or waterway in which he is working, in the process of searching for the place where the welding operations are to be effected.

The present invention provides an attachment comprising a tubular helmet extension 20 which is mounted on the forward face of the helmet 12 opposite the outlet opening 12^d, being supported on its upper side by a pair of hinges 21 which are secured to the tubular extension and to the wall of the helmet, as shown particularly in Figs. 1 and 5. The tubular extension 20 is formed preferably of molded plastic insulating material or of metal covered with insulating material, such as rubber, and it is provided around its inner open end with an annular flange 22, formed of rubber or the like, which is adapted to seat against the curved end face of the helmet 12 when the tubular extension 20 is in its normal horizontal position, as shown in Figs. 1 and 5, thus forming a resilient connection between the helmet 12 and the tubular extension 20. When the tubular extension 20 is in its horizontal position just referred to, the annular rubber flange 22 which projects outwardly therefrom, and which conforms to the surface of the helmet 12, is adapted to be engaged beneath the tubular extension by a leaf spring 23 which is secured to the helmet 12 by rivets 24 and which has a curved extremity 23^a adapted to permit the flange 22 to be snapped inwardly under the spring when the tubular extension 20 is swung downwardly from the position shown by dotted lines in Fig. 1. This tubular extension is adapted to contain a ground colored lens and to support the illuminating apparatus and the water jet device by which the steam, bubbles and sparks are carried out of the field of operations, and, during the time that the diver is walking about on the bottom searching for the field of work, this attachment 20 occupies the upper tilted position shown by dotted lines in Fig. 1, but, when he is ready to begin the welding operation, the attachment 20 is lowered to the position shown by full lines in Figs. 1 and 5, whereupon the flange 22 snaps into position beneath the spring latch member 23, and the parts are retained in these positions until the welding is completed.

The tubular extension 20 is provided at its rear end, adjacent the outlet 12^d of the helmet 12, with an annular inwardly extending shoulder 20^a provided with an annular inwardly extending flange 20^b, and a lens or glass plate 25 is mounted within the shoulder 20^a and against the flange 20^b, being held in fluid tight engagement therewith by rubber gaskets 26. A metal ring 27 seats within the shoulder 20^a against the innermost gasket 26 and this ring and the gaskets are secured to the flange 20^b by a series of screws 28. The plate or lens 25 is preferably formed of clear glass and, by means of the construction just described, a fluid tight connection is provided between it and the wall of the tubular extension 20, so that any moisture which finds its way into the space between the lens 16 and the lens 25 cannot enter the inner chamber of the tubular extension.

Within this inner chamber there is mounted a ground glass magnifying lens 30, which is formed preferably of plain clear glass and which is carried by a lens frame 31. This lens frame is circular in form and is adapted to be adjusted longitudinally of the focal axis of the lens 30 through the operation of adjusting screws 32 which have threaded engagement with apertures formed in opposite sides of the frame 31 and which rotatably engage apertures formed in the annular shoulder 20^a at the rear end of the extension 20. These adjusting screws 32 are provided with heads 32^a, adapted to be engaged by a screwdriver, which are accessible to the operator when the tubular extension 20 has been swung upwardly to the position shown by dotted lines in Fig. 1, so that the operator may then employ a screwdriver for adjusting the longitudinal position of the lens 30 within the chamber of the tubular extension. The opposite or forward ends of the adjusting screws 32 are arranged to have rotatable engagement with apertures formed in a metal ring 33 and the adjusting screws are provided with detachable heads 32^b which revolve in recesses formed in the ring 33, whereby the adjusting screws are held against endwise movement when they are turned about their axes, the ring 33 being secured to another ring 34 which contacts its forward face and which is secured in position within the extension 20 by screws 35. The frame 31 carrying the lens 30 and the two rings 33 and 34 are inserted into the tubular extension 20 from the forward end thereof and after the adjusting screws 32 have been moved into engagement with the ring 33 and the heads 32^b have been applied, the two rings 33 and 34 are secured together and the screws 35 are then inserted to secure the ring 34 in place.

A channel-shaped rubber insulating ring 39, carrying a colored glass plate 40 and a clear glass plate 43 within its channel, is mounted on the forward side of the ring 34 and a ring 41, having radial perforations 41^a extending therethrough, seats against the forward surface of the insulating ring 39. The rings 39 and 41 are secured to the ring 34 by means of a series of screws 42. When these screws are tightened, the insulating ring 39 is compressed longitudinally of the axis of the extension 20 and is expanded in a radial direction so that a fluid tight connection is thereby established between the ring 34 and the tubular extension 20. The ring 41 is provided with a plurality of radiating cylindrical apertures 41^a which are arranged to register with a series of apertures 20^d formed in the tubular extension 20, for a purpose hereinafter described. The two plates 40 and 43 are both employed so that the plate 43 may be made thick enough to withstand the water pressure while the inner colored plate 40 may be made comparatively thin.

Air under pressure is introduced into the chamber of the tubular extension 20 through a flexible conduit 44 leading from the interior of the helmet 12 and a check valve 45 is connected in this conduit close to the helmet 12 to prevent water from entering the helmet 12 in case the conduit 44 or the extension 20 is broken. The purpose of introducing air under pressure into the chamber of the attachment is to balance the water pressure on its outer side sufficiently to prevent collapse of the tubular extension or the lenses when operating in substantial depths of water. An adjustable release valve 46 is mounted in the wall of the attachment 20 to relieve the air pressure in the inner chamber if it rises to an undue extent. If desired, the conduit

44 may lead from the water surface directly into the extension 20, but the arrangement shown is preferable because it is desirable to limit, as far as possible, the number of connections extending to the surface.

At the forward end of the tubular extension 20 a ring-shaped nozzle 50 is secured against the outer face of the ring 41 and water under pressure is supplied to this nozzle through suitable connections comprising an elbow 51, a flexible hose or conduit 52, a hinged joint connection 53, a valve 54 and a supply conduit 55. The water which is thus introduced under pressure into the nozzle 50 is discharged through a series of small openings 50a to form an annular series of outwardly converging jets, the apex of which is located at the point 56. These jets thus define a cone-shaped area or region from which the lake or sea water is carried outwardly by direct action or by suction, together with the steam, bubbles and sparks produced by the welding operation, so that all elements tending to obstruct the vision are removed from this region 57 between the apex 56 of the cone and the face of the glass lens 40. The water jets may produce a partial vacuum in the immediate vicinity of the lens 40. The result thus obtained may be regulated by the diver through the adjustment of the valve 54. In Fig. 5, this welding zone is shown as being within but near the apex of the cone-shaped cavity where two plates 59 and 60 are shown as contacting along the surfaces 61 which are to be united by a butt weld. The torch thus operates in an area which is substantially free of steam, bubbles, sparks and the like, so that the vision of the diver is unobstructed during the welding operation. By properly adjusting the position of the ground glass lens 30 longitudinally of the tubular extension 20, the area where the weld is to be made may be magnified as desired to suit the eyes of the diver and the character of the work being done.

To improve the diver's view of the work within the cone-shaped cavity, the region where the weld is to take place is preferably illuminated by a series of lamps 63 which are mounted around the forward end of the tubular helmet extension 20. Each lamp comprises a tube 64 having mounted in the forward end thereof an insulating ring 65 in which there is secured an electric light bulb 66. Each tube 64 has an inclined forward end face against which there is mounted a glass lens or plate 67 secured in place by a metal ring 68 having a threaded engagement with the end of the tube. Each lamp bulb 66 may be energized by a pair of flashlight batteries 69 which are mounted within the tube 64 and connected in series, these batteries being pressed against the base of the bulb 66 by a coil spring 70. When the operator does not desire to employ the batteries 69, they may be disconnected and the lamps energized by electrical conductors contained in cables 71 which extend to the surface of the water and are controlled by one or more electric switches 72. These electric cables lead into the tubes 64 through insulating plates 73 and metal plates 75 which are secured to the rear ends of the tubes 64 by screws 76. The closures for the tubes 64 should be fluid tight so that water will not disturb any parts of the electrical connections.

The electric lamps 63 are carried by a pair of metal rings 77 which are clamped on the forward end portion of the tubular extension 20 by means of set screws 78. These rings are provided with

aligning apertures in which the tubes 64 are mounted and the tubes are held in adjusted positions with respect to the rings by set screws 80 which may be released to permit the lamps to be adjusted longitudinally for the purpose of varying the position of the point on which the light rays are concentrated. For the purpose of directing the light rays from the bulb 66 toward a common point, each tube 64 is provided with a reflector 81 located above the electric bulb and behind the glass plate or lens 67 so that the light rays 82 emitted by each bulb 66 are directed downwardly and forwardly to converge at and rearwardly of the rear surfaces of the plates 59

- 5 10 15 20 25 30
10. reflector 81 located above the electric bulb and behind the glass plate or lens 67 so that the light rays 82 emitted by each bulb 66 are directed downwardly and forwardly to converge at and rearwardly of the rear surfaces of the plates 59 and 60 which are to be welded. In this way the interior of the cone-shaped area in which the welding takes place is illuminated so that the crack 61 in the plates is clearly visible to the operator of the welding torch.
15. During the welding operation, the water around the forward end of the tubular extension 20 and the site of the weld, which water is heated by the welding torch, is drawn inwardly through the apertures 20a in the extension 20 and the registering apertures 41a in the ring 41 by the suction of the jets discharged by the nozzle 50, and is then carried forwardly by the jets so that the water heated by the torch is circulated continually and brought to the site of the weld to heat the parts to be welded, thus facilitating the welding operation.

When the welding operation has been completed, the valve 54 may be operated to shut off the flow of water and the switch or switches 72 35 may be actuated to deenergize the lamps 63, whereupon the tubular extension 20 and the parts carried thereby may be swung upwardly to the position shown by dotted lines in Fig. 1. During this operation, the hinged joint 53 in the water 40 connection permits the upward movement of the flexible conduit 52. The operator is then enabled to look through the clear glass lens 16 in the helmet 12 as he moves away from the place where the welding operation has been effected.

- 45 50 55 60 65
45. From the foregoing description it will be apparent that the present invention provides an attachment for a diver's helmet which permits the diver to move about at the bottom of the body of water where he is to carry on his welding operations, with the tubular extension 20 then elevated so that a clear vision of the diver's surroundings may be obtained through the clear glass lens 16. When the work to be welded has been located, and the diver is prepared to begin the welding operation, the helmet extension 20 may be swung downwardly to permit the rubber ring 22 to be automatically latched by the spring 23, whereupon the tubular extension 20 is held firmly in position and the operator may then look through the lenses 25, 30 and 40 to view the operation of the welding torch without danger of injuring his eyes, while at the same time obtaining a clear vision of the work due to the operation of the lamps 63 to the fact that the steam, bubbles and sparks have been carried by the jets of water out of the area of the welding operation, and to the further fact that the parts to be welded are magnified by the lens 30.

Although one form of the invention has been shown and described by way of illustration, it will be understood that the invention may be constructed in various other embodiments coming within the scope of the appended claims.

I claim:

- 70 75 1. In a device of the class described, a diver's

helmet constructed and mounted to form a water tight closure for the head of the diver and having an outlet opening, a lens mounted over said opening, and means for causing jets of water under pressure to form an area opposite said lens which is substantially free of vision obstructing elements when said helmet is submerged and welding operations are carried on in said space.

2. An attachment for a diver's helmet constructed and mounted to form a water tight closure for the head of the diver and having an outlet opening, comprising a tubular member adapted to be mounted on said helmet around said opening, and means including a circular nozzle carried by said member for ejecting jets of water away from the mouth of said member when said member is submerged.

3. An attachment for a diver's helmet constructed and mounted to form a water tight closure for the head of the diver and having an opening, comprising a tubular extension adapted to extend outwardly from said opening, a lens mounted in said extension, and means including a nozzle mounted on said extension for directing outwardly converging jets of liquid under pressure away from the outer end of said extension when said extension is submerged.
